ELEVATOR

Application filed March 24, 1928. Serial No. 264,345.

This invention relates particularly to that type of elevators now used in elevating motor vehicles for cleaning, lubricating, and so on.

It is common practice in devices of this kind to effect the elevation of a reciprocating piston, with the load thereon, by introducing into the cylinder and below the piston a suitable liquid under pressure. This liquid is ordinarily supplied from a tank where air pressure is applied thereto or removed therefrom, or it may be contained within the piston and cylinder and transferred directly from one to the other as the piston rises or falls. In either case the movement of the piston is controlled by the air pressure, but since air is elastic the closing of a valve in the air line does not immediately stop the movement of the piston.

It is the object of the present invention to provide a device of the character indicated wherein the piston is under complete control of the operator and may be stopped instantly, thereby eliminating the dangers present in those devices where a gradual stopping only can be effected.

It is also an object of the invention to provide a device of the character indicated wherein the piston is automatically cushioned at the close of its upward movement thereby eliminating the sudden jar now experienced in known devices of this kind.

It is a still further object of the invention to provide a device of the character indicated that will be simple in construction, economical to manufacture, and highly efficient in its practical application.

With these and various other objects in view, the invention may consist of certain novel features of construction and operation, as will be more fully described and particularly pointed out in the specification, drawings and claims appended hereto.

In the drawings:

Figure 1 is a vertical transverse section through the device, partly in elevation.

Figure 2 is an enlarged sectional view of the lower piston bearing.

Referring now more particularly to the drawings, we show at 1 a vertically positioned cylinder suitably mounted in a hole

in the ground as 2. At the upper end of this cylinder is mounted a packing or stuffing box of the type shown in Figure 2, and in the center of its lower end is formed a passage 3. Concentrically arranged in cylinder 1 and communicating with the passage 3 but closed off from the interior of the cylinder, is an upwardly extending conduit 4 converging somewhat at its upper end as at 5 and provided with a number of orifices in its side wall near said upper end as indicated at 6. Communicating with the passage 3 is a pipe 7 extending to any readily accessible position where it is fitted with a valve 8 and thence back to and communicating with the cylinder 1 at any suitable point as 9.

Concentrically mounted in cylinder 1 is a vertically movable cylinder or piston 10 of less diameter than cylinder 1 and extending through packing box 11. Bearing rings as 12 and 13 are fitted in cylinder 1, both bearings being provided with passages 14 and also functioning as a stop for cylinder 10 which is provided with a flange as 15 for this purpose. The upper end of the cylinder 10 carries any suitable type of head as 16. This cylinder is entirely closed except at the bottom where it is provided with an opening 17 through which the conduit 4 passes, and it is fitted with a packing or stuffing box 18 removably mounted therein as indicated at 18a.

At 19 we show a conduit passing upwardly through the bottom of cylinder 1 and through conduit 4 to the upper part of cylinder 10 when in its lowest position. Conduit 19 also extends to any readily accessible position, preferably adjacent valve 8, where it is fitted with a valve 20, and thence to a source of air pressure not shown.

When the elevator has been constructed and assembled as above set forth, and the pipe 7 and the cylinders 1 and 10 filled with oil, the latter to a suitable level as 21, it is ready for use. With the valve 8 closed the valve 20 may be opened and air under any desire pressure introduced into the cylinder 10 above the level of the liquid therein. There will be no movement of the cylinder 10 at this time because the pressure applied to the liquid bears against the closed valve 100.

8, being carried through orifices 6 and pipe 7, but when the valve 8 is opened the oil is forced into the cylinder 1 and against the bottom of cylinder 10 thereby causing it to rise. Since the liquid is carried in a closed circuit between the cylinders 1 and 10 it is merely transferred as desired from one to the other so that when the valve 8 is again closed the movement of the cylinder 10 is instantaneously halted, regardless of the air pressure acting thereon. As the cylinder 10 approaches the upper limit of its movement, with valve 8 open, the bearing 18 moves over and successively closes the orifices 6 thereby gradually cutting off the flow of liquid therethrough and preventing the flange 15 from contacting with the stop 13 with a jar. The movement of the liquid is, of course, reversed when valve 20 is opened to permit reduction of the air pressure in cylinder 10. Even though the air pressure be exhausted to atmospheric pressure in cylinder 10 when there is a load on head 16, the downward movement of the cylinder is instantly stopped when valve 8 is closed.

It is to be understood, of course, that while we have particularly referred to oil as the liquid used in the device, any suitable non-compressible liquid may be used. It is to be further understood that changes in form, construction and method of assembly and operation may be made within the scope of the appended claims.

We claim:

35 1. An elevator comprising a hollow cylinder, a second hollow cylinder mounted for vertical movement therein and forming a pressure chamber therewith, a valve controlled conduit communicating with said cylinders and extending into and connected to said second cylinder and having an opening therein, a non-compressible fluid filling said conduit and pressure chamber and a portion of said second cylinder to a point above said opening, means mounted on the second cylinder adapted to close said opening toward the close of its upward movement, means for introducing a compressible fluid into the second cylinder and for exhausting the same therefrom.

40 2. An elevator comprising a hollow cylinder, a hollow piston mounted to reciprocate relative thereto and forming a pressure chamber therewith, a valve controlled conduit communicating directly with the piston and cylinder, an incompressible fluid filling said conduit and pressure chamber and a portion of said piston, and valve controlled means to introduce a compressible fluid into the piston.

45 3. An elevator comprising a hollow cylinder, a hollow piston mounted to reciprocate relative thereto, a valve controlled conduit communicating directly with the piston and cylinder, piston controlled valve means for

closing and opening said conduit, an incompressible fluid filling said pressure chamber and conduit and a portion of said piston, and valve controlled means for introducing a compressible fluid into said piston. 70

4. In an elevator, a hollow cylinder, a second hollow cylinder vertically movable with respect to the first cylinder, and forming a pressure chamber therewith, a conduit directly communicating with the pressure chamber and opening into the second cylinder, a non-compressible fluid in said conduit and in said pressure chamber, and in the second cylinder, means controlled by the second cylinder to shut off the flow of the fluid into the conduit from the second cylinder as the latter approaches the limit of its upward movement, means for introducing a compressible fluid into the second cylinder, and means for controlling the exhaust of the compressible fluid from the second cylinder. 75 80 85

5. In combination with a hollow cylinder and a hollow piston reciprocable with respect to each other, a non-compressible fluid circuit including the cylinder and piston interior, means to supply a compressible fluid to the surface of the non-compressible fluid in the piston, means to exhaust the compressible fluid from the piston, and automatic means carried by said piston and operable by the upward movement of the piston to interrupt said circuit as the piston approaches the limit of its upward movement. 90 95

6. In an elevator, a hollow cylinder, a second hollow cylinder reciprocable with and spaced from the first cylinder, a conduit communicating with the space between the cylinders and with the interior of the second cylinder, a non-compressible fluid in the conduit, in the space between the cylinders, and in the second cylinder, means carried by and controlled by the movement of the second cylinder to close said communication between the conduit and the second cylinder as the latter approaches a predetermined position, means to supply a compressible fluid to the surface of the non-compressible fluid in the second cylinder, and means to exhaust said compressible fluid from the second cylinder. 100 105 110

7. In a lifting device, the combination of a cylinder, a hollow piston reciprocably mounted therein and spaced therefrom, spacing members disposed between said piston and cylinder, one of said members forming a stop adapted to be engaged by a portion of said piston, fixed means for supplying fluid pressure to said piston and cylinder for moving said piston, additional fixed means for conducting fluid from said piston to said cylinder, and means on said piston cooperating with said additional fixed means for arresting movement of said piston and preventing violent contact between said stop and piston portion. 115 120 125

8. In a lifting device, the combination of

a cylinder, a hollow piston reciprocably mounted therein, fixed means extending through said cylinder and piston and extending to a point adjacent the top of said piston in inoperative position, a fixed member extending into said piston and connected to a member connected to said cylinder for conducting fluid under pressure from the inside of said piston to said cylinder, and means on said piston cooperating with said fixed member for closing communication between said piston and cylinder after a predetermined movement of said piston.

9. In a lifting device, the combination of a cylinder, a hollow piston reciprocably mounted therein, fixed means extending through said cylinder and piston and extending to a point adjacent the top of said piston in inoperative position, a fixed member extending into said piston and connected to a member connected to said cylinder, said fixed member and said last named member being constantly filled with a substantially incompressible fluid, means for introducing another fluid to said piston for moving said first named fluid from said piston to said cylinder to thereby move said piston, and means on said piston cooperating with said fixed member for closing communication between said piston and cylinder after a predetermined movement of said piston.
